DECORATIVE SHEET MATERIAL AND
METHOD OF USING THE SAME

James M. W. Chamberlain, Akron, Ohio

Application March 3, 1939, Serial No. 259,694

9 Claims. (Cl. 41—34)

This invention relates to decorative sheet material, adapted for the formation therefrom of decorative design elements adapted for assembly upon a suitable background or support, and to methods of using such material.

Its chief objects are to provide decorative elements that can be easily formed and easily secured in desired positions upon the background or support; to provide design elements or units that can be readily removed from the background or support and without damage to the latter; to provide elements or units readily adapted to afford two-color or multi-color effects, in conjunction with other advantages indicated in this statement of objects; and to provide design elements adapted, in conjunction with other advantages, to afford three-dimensional effects.

I have found that thinly sheeted materials such, for example as the material known commercially as Pliofilm and described in Calvert United States Patent No. 1,989,632, and the material known commercially as Koroseal and described in Semon United States Patent No. 1,929,453, inherently carry an electric charge which causes pieces cut or torn from the sheet to adhere quite strongly to a surface such as that of a wall, ceiling or floor of a room, or a table or the like, without the use of any adhesive, and to continue so to adhere for a long period of time and even for days, and that this characteristic of such materials can be dependably utilized for producing a great variety of temporary and even somewhat permanent decorative effects, and that by such use all of the advantages indicated in the above statement of objects can be obtained.

I have found that while one part of a decorative unit or element of such material is shaped flat for adhesion to the supporting surface another part of the same piece, as by heating and pressing, can be given a position "out of the plane" of the flat attachment portion or portions, as by forming the sheet with spaced apart bays or with a succession of series of bays or corrugations or pleats, so that three-dimensional effects can be provided and so that the sheet or strip can be bent "in its own plane" to form various designs and yet be secured firmly to a wall or a ceiling, for example, by the electrical effect in the flat attachment portion or portions.

I have found also that sheets of the material can be mounted one upon another with both of them securely held in place by the electrical effect, so that two-color and multi-color combinations can readily be provided.

I have found also that the strength of the at- 55

traction or adhesion can be increased by rubbing the element or elements, after they are in place, with a soft material such as silk or wool, and this apparently produces the desired result not only by forcing the sheet, or its attachment portion, into more snugly fitting relation to the support, but also by increasing the electrical effect.

As the materials can be made in many colors and have a pleasing surface finish, very attractive designs can be made of them.

The invention is adapted for many uses, including not only decoration but also advertising purposes, primary education, games of amusement and of skill, and household-bulletin purposes, as a few examples.

Of the accompanying drawing:

Fig. 1 is a face view of a sheet of the material having upon it marked outlines of design elements or units.

Fig. 2 is an edge-wise view of a sheet of the material providing a three-dimensional effect and adapted for bending the sheet, or a strip formed from it, "in its own plane."

Fig. 3 is a face view of the sheet shown in Fig. 2, the dotted lines indicating the possibility of mounting one of the strips in a form such that it is bent "in its own plane."

Fig. 3A shows a strip similar to that shown in Fig. 3, in approximately the form of a circle.

Fig. 4 is a face view of a unit of the material adapted for producing a two-color effect.

Fig. 5 is a face view of two pieces of the material assembled to provide a two-color silhouette and adapted to be cut into smaller pieces to provide a jig-saw puzzle.

Fig. 6 is a face view of assembled pieces of the material providing a four-color effect.

Fig. 7 is a face view of three pieces of the material adapted to be placed one upon another to provide a United States flag in proper colors, as in Fig. 8.

Fig. 9 is a face view of letter-shaped pieces of the material adapted for primary educational purposes or for the display of indicia.

So far as applicant knows, no very satisfactory way has been found as yet for printing cut-out lines on material of this character, and for this reason he prefers to provide the severance lines by means of rows of perforations, but his invention and the appended claims contemplate that more satisfactory procedure for printing lines upon the material may be arrived at.

Referring to the drawing, Fig. 1 represents a sheet of the material 10 marked or perforated as at 11, 11 for separation of the sheet by cutting

or by tearing to provide silhouette figures for decorative purposes, silver stars 12, 12, a yellow crescent moon 13 and a black witch 14 being shown merely as examples.

Figs. 2 and 3 represent a sheet of the material 15 preliminarily formed with flat attachment zones 16, 16 alternating with transversely corrugated or pleated zones 17, 17 and with parallel longitudinal marked lines or rows of perforations 18, 18 adapting the sheet to be cut or torn into strips each of which, by reason of the corrugated or pleated zones is adapted to be bent "in its own plane," so to speak, which makes possible a wide variety of wall designs. For example, one of the strips can be caused to adhere to the wall in approximately the form of a circle, as shown in dotted lines with respect to the lowest strip in Fig. 3A.

In Fig. 4 a two-color effect is provided by first adhering to the wall a white sheet 19 and then placing upon it a black sheet 20 having portions removed so that the white sheet will show through openings left by the portions removed from the black sheet 20.

Fig. 5 shows a sheet in the form of a silhouette of a human head with markings for cutting it into a jig-saw puzzle. A sheet 21 of one color can be used for the face portions and a sheet 22 of another color for the hair, for a two color effect, with all of the pieces fitting together, nevertheless, as a complete human head.

Possible uses of this type of embodiment of the invention is that a hostess clever with the scissors can have silhouette likenesses of her guests as temporary wall decorations, with humorous or incongruous variations of costume, associated objects or the like; or, in jig-saw puzzle form the pieces can be used for score keeping in connection with or as an adjunct to a game, the picture being so cut that several parts are closely similar so that there is likelihood of a part being incorrectly placed, with a sacrifice of the point scored, or with any other suitable penalty; or the piecing together of similar pictures can be made a game in itself, with accuracy and the time required determining the winner, as some dexterity is required in placing the pieces accurately, because of their propensity for jumping into contact with the wall when brought close to it.

Fig. 6 represents a four-color design produced by first placing for example a solid white sheet 23, then a cut-out sheet 24 of black having for example a cut-out with the outline 24a of a daisy, and then placing within the outline of the daisy, at its center, a yellow disc 25 and upon that a smaller black disc 26, and at the middle of each petal a small red stripe element 27.

Fig. 7 illustrates suitable shaped pieces for building up a United States flag, such as is shown in Fig. 8, by first placing a solid red sheet 28, then upon it a white sheet 29 formed with strip portions 29a, 29a, for the white strips of the flag, joined at the left margin by a web portion 29b of the same sheet, and then, upon the white member, a blue sheet 30 having star-shaped cut-outs 30a, 30a.

The web portion 29b of the white member being first put in proper position, the stiffness of the material against bending in its own plane is sufficient to assure that the strip portions 29a of the white sheet will be in proper relation when applied by progression from the web portion 29b toward their free ends.

Fig. 9 illustrates the use of the invention for educational purposes, such as the teaching of the

alphabet and spelling, and the letters can be conveniently used either alone or in association with pictorial representations such as are illustrated in the other figures.

The invention is susceptible of various further modifications without sacrifice of all of the advantages set out in the above statement of objects.

In the appended claims the words "an overlay design element" are used as meaning an element which is given prominence by reason of contrast, at its outline, with the surface of the support upon which it is overlaid, as in the accompanying drawing, for example, as distinguished from an element occupying less than substantially the entire area within the outline that the sheet is to have when mounted upon the support, as in a printed bread-wrapper, for example.

I claim:

1. A design element comprising a piece of flexible sheet material inherently carrying an electric charge alone adapting it to adhere to a support and having at least one normally flat attachment zone and at least one zone normally out of the plane of the attachment zone.

2. A design element comprising a piece of flexible sheet material inherently carrying an electric charge alone adapting it to adhere to a support and having at least one normally flat attachment zone and at least one zone in which the material forms at least one bay out of the plane of the attachment zone to adapt the piece to be bent in the plane of the attachment zone.

3. A design element comprising a piece of flexible sheet material inherently carrying an electric charge alone adapting it to adhere to a support and having at least one normally flat attachment zone and at least one zone in which the material is corrugated to adapt the piece to be bent in the plane of the attachment zone.

4. A design assembly comprising two differently colored pieces of sheet material inherently carrying an electric charge alone adapting them to adhere to a support, the sheets being held in adhering relation one upon the other by the electric charge and the outer sheet being shaped to expose a part of the under sheet.

5. The method of providing and displaying a design which comprises forming the design from a piece of sheet material inherently carrying an electric charge such as alone to cause it to adhere to a support, and causing it to adhere to a support by reason of the electrical charge alone.

6. The method of providing and displaying a design which comprises forming the design from a piece of sheet material inherently carrying an electric charge such as alone to cause it to adhere to a support, causing it to adhere to a support by reason of the electrical charge alone, and thereafter rubbing the piece with a soft, electrifying material.

7. The method of providing and displaying a design which comprises forming the design from a piece of sheet material inherently carrying an electric charge such as alone to cause it to adhere to a support, causing it to adhere to a support by reason of the electrical charge alone, and so forming and causing to adhere to the first piece a second piece of another color so shaped as to expose a part of the first piece.

8. The method of providing and displaying a design which comprises forming, of sheet material inherently carrying an electric charge such as alone to cause it to adhere to a support, a

piece having at least one normally flat attachment portion and at least one portion normally out of the plane of the attachment portion, and causing the attachment portion to adhere to a support by reason of the electrical charge alone.

9. The method of providing and displaying a design which comprises forming, of sheet material inherently carrying an electric charge alone adapting it to adhere to a support, a piece shaped

with at least one normally flat attachment portion and at least one bay out of the plane of the attachment portion, and causing the piece to adhere to a support by reason of the electrical charge alone, and with the bay distorted so that the adjacent portions of the piece stand in a new angular relation to each other.

JAMES M. W. CHAMBERLAIN.
